(57) **CLAIM**

The ornamental design for a plumbing fitting, as shown and described.

DESCRIPTION

FIG. 1 is a right, top, front perspective view of a plumbing fitting embodying our new design;

FIG. 2 is a front elevational view thereof, the rear elevational view thereof being a mirror image of the front shown;

FIG. 3 is a right side elevational view thereof;

FIG. 4 is a left side elevational view thereof; and,

FIG. 5 is a top plan view thereof, the bottom plan view thereof being a mirror image of the top shown.

The broken line representations in the figures are for the purpose of illustration only, and form no part of the claimed design.

In a preferred embodiment, the nature of this product is as a plumbing fitting which in certain forms can be a faucet, a shower control and/or handle, valve bonnet and escutcheon components therefor.
